REFRIGERATING APPARATUS

Harry M. Williams, Dayton, Ohio, assignor, by
mesne assignments, to General Motors Cor-
poration, a corporation of Delaware

Application August 31, 1931, Serial No. 560,279

7 Claims. (Cl. 62—115)

This invention relates to refrigerating apparatus of the type which includes a cooling element adapted to be placed in the path of a cooling medium and which is adapted to be maintained normally at a temperature causing solidification of a part of said medium flowing thereover and more particularly to improved means for quickly removing the solidified medium accumulated on said cooling element.

10 One of the objects of this invention is to provide improved means for freeing the cooling element from frost and ice accumulated thereon.

More specifically it is an object to provide a refrigerating cabinet with a cooling element for 15 cooling food articles stored in said cabinet and to arrange said cooling element in such a manner whereby circulating air within the cabinet is circulated over said cooling element and to arrange said cabinet and cooling element in such 20 a manner so that said element may be exposed to a medium of a higher temperature than the circulating air within the cabinet for defrosting said element. In practicing this invention it is a further object to utilize the warm air outside 25 of the refrigerating cabinet and circulate said warm air over the cooling element for defrosting said element while at the same time preventing said warm air from entering the food storage compartment of the refrigerating cabinet.

30 Further objects and advantages of the present invention will be apparent from the following description, reference being had to the accompanying drawings, wherein a preferred form of the present invention is clearly shown.

35 In the drawings:

Fig. 1 is a diagrammatic illustration of a refrigerating apparatus embodying features of the invention;

Fig. 2 is an enlarged view of a portion of the apparatus shown in Fig. 1 and showing a modified arrangement for controlling the operation of the refrigerating apparatus;

Fig. 3 is a diagrammatic illustration of a modified form of refrigerating apparatus embodying 45 features of the invention;

Fig. 4 is a view taken on the line 4—4 of Fig. 1; and

Fig. 5 is an enlarged view in cross-section of a portion of the refrigerating apparatus shown in 50 Fig. 3.

It is usual to refrigerate rooms, compartments, cabinets and the like to place a cooling element such as an evaporator in the cabinet to be cooled and circulate refrigerant through the cooling 55 element by means of a refrigerant circulating

element which usually operates automatically in response to normal conditions within the apparatus to chill the cooling element and induce the circulation of air in the space to be cooled. This cooling element soon becomes coated with frost 5 and ice formed by the freezing of water condensing on the cooling element from the circulating air and this frost and ice forms a resistance to the transfer of heat from the air to the cooling element and thus reduces the efficiency 10 of the system. Since the refrigerating requirements of the cabinet vary from time to time and since refrigeration is produced by the apparatus at a substantially uniform rate, which rate must be slightly higher than the maximum requirement of the space to be cooled, it is usual to operate the refrigerating system intermittently in order to prevent cooling the space below the desired temperature.

In practicing this invention it is a further object to prevent operation of the refrigerant circulating element in response to normal conditions within the apparatus when it is desired to defrost the cooling element. This is accomplished in a manner hereinafter described.

Referring to the drawings, and particularly to Figs. 1 and 4, the numeral 20 designates in general a refrigerator cabinet embodying features of my invention. The cabinet 20 includes an insulated shelf 21. The shelf 21 divides the cabinet 30 into a food storage compartment 23 and a compartment 24 in which is disposed a cooling element or evaporator 26.

The evaporator 26 is formed of a continuous coil of pipe and is supported upon supports 28 35 in the compartment 24. Liquid refrigerant is supplied to the evaporator through a liquid conduit 30 under the control of a pressure responsive expansion valve 31 which increases the flow of refrigerant to the evaporator as the pressure 40 therein decreases and decreases the flow of refrigerant to the evaporator as the pressure increases. Vaporized refrigerant is withdrawn from the evaporator through a vapor conduit 32, both conduits 30 and 32 being suitably connected to a refrigerant circulating element 35. The element 35 includes a condenser 37, receiver 38, to which the conduit 30 is connected, a compressor 40 and a motor 42 for driving the compressor. The motor is supplied with current through the power mains 45 under the control of an automatic switch 47. The switch 47 is actuated by means of a thermostat 48 disposed in the compartment 23 and responsive to 50 55

the temperatures therein for actuating said switch for starting and stopping the motor 42.

In order to provide for the proper circulation of air within the cabinet 20, I have provided a fan 52 which is driven by electric motor 54. The motor 54 is connected directly across the power mains 45 and is preferably operated continuously. However, if desired, any suitable switch may be placed in the circuit to the motor 54 for interrupting the flow of current thereto. The air within the compartment 20 circulates or passes from the compartment 24 through an elongated opening 56, flue 58 and into compartment 23 and is returned to the compartment 24 through an elongated opening 57. Thus, it will be apparent that the fan 52 will force the air over the cooling element 26 through opening 56 into compartment 23 whence it returns to compartment 24 through opening 57 to be recirculated by fan 52.

In many instances the cooling element 26 is employed to maintain frozen food articles in a frozen condition and consequently to maintain the temperature of the storage or display compartment in which they are stored below the thawing point of such articles. Moisture from the foods and from the air is condensed and frozen on the cooling element, which frozen moisture or frost insulates the element. For this reason it is desirable to defrost the evaporator occasionally and such defrosting should be done quickly in order to prevent the temperature of the food storage compartment from rising above the thawing point of said articles.

In accordance with this invention, I provide means for quickly defrosting the cooling element and for sealing the food storage compartment against the warming effect of defrosting. This means comprises utilizing the warm air on the outside of the cabinet 20 and circulating the warm air over the cooling element 26 by means of fan 52. In order to accomplish this, I have provided doors 60 and 61 located at opposite ends of the compartment 24. Doors 60 and 61 normally close openings 63 and 64 respectively. These doors are arranged to be swung inwardly for admitting outside air into the compartment 24 and I have also arranged these doors so that they will seal the openings 56 and 57 to prevent the warm air in the compartment 24 from entering the food storage compartment 23. In order to prevent operation of the refrigerant circulating element when it is desired to defrost the cooling element 26, I have provided a switch 65 which may be opened to interrupt the circuit to the electric motor 42. If desired, an electric heating element 67 may be placed in the compartment 24 for increasing the temperature of the air being circulated over the cooling element 26 for reducing the time required for defrosting the cooling element 26. The circuit through the heating element 67 is controlled by switch 70. As shown in Figs. 1 and 4 the food storage compartment 23 is provided with a plurality of shelves 72 preferably of the open-work type adapted to support food articles to be refrigerated. The cabinet 20 is also provided with a plurality of insulated walls 73, 74, 75, 76, 77 and 78. Walls 75 and 77 are provided with transparent portions 90 and 91 respectively. Wall 78 is provided with one or more openings 79 closed by one or more doors 84. The shelf 21 which serves to support articles to be refrigerated is insulated so as to prevent any of the heat which is present in compartment 24

during defrosting periods from warming up the compartment 23.

From the foregoing it will be noted that I have provided a refrigerating cabinet for the storage and display of food articles and that I have arranged said cabinet and cooling element in such a manner that the cooling element may be readily and quickly defrosted without interfering with the temperatures sought to be maintained in the food storage compartment to any material extent. It will also be noted that I have accomplished this by utilizing the warm air outside of the refrigerator cabinet for defrosting the cooling element and I have arranged for preventing said warm air from entering the food storage compartment. It will also be noted that the electric fan 52 is preferably operated continuously for circulating the cool air through the compartments 23 and 24 or for circulating the warm air from the outside of the cabinet over the cooling element at defrosting periods. Furthermore, it will be noted that I have provided auxiliary means for increasing the temperature of the air being circulated over the cooling element during defrosting periods.

Referring now to Fig. 2, it will be noted that I have provided a modified form of control for the refrigerating apparatus. In this embodiment I have provided a control apparatus 80 which comprises movable levers 81 and 82 which actuate movable contacts 83 and 85. This control apparatus 80 is arranged to be actuated by roller 87 carried by door 60. As shown in the drawings the circuit through the motor 42, which drives compressor 40, is closed and the circuit through the motor 54 which drives fan 52 is also closed while the circuit to the electric heater 67 is open. When it is desired to defrost the cooling element 26, the door 60 is moved inwardly and in so doing the roller 87 engages lever 82 to move the contact member 83 downwardly to engage stationary contact 94 to thereby close the circuit to the electric heater 67. When this movement of the control apparatus 80 takes place, the movable contact member 85 is separated from stationary contact member 88 to thereby interrupt the circuit to the electric motor 42 to render the refrigerant circulating element inoperative at this time. As shown in Fig. 2, the roller 87 is adapted to engage a member 97 carried by the insulated shelf 21 to hold the door 60 in the position shown in dot and dash lines in Fig. 2 of the drawings. The member 97 is preferably resilient to provide a sufficient frictional connection between itself and the roller 87 to hold the door 60 in the dot and dash line position. When the door 60 is in this position it will engage a gasket seal member 99 to seal the compartment 24 from the compartment 23. When the door 60 is being moved to close opening 63 the roller member 87 will engage lever 81 which is at this time in a substantially vertical position to thus return the control apparatus to its position shown in Fig. 2 to thus interrupt the circuit to the electric heater and close the circuit to the electric motor 42. When this takes place, and the switch 47 has closed its contacts, the motor 42 will operate to drive the compressor to supply refrigeration to the cooling element 26. A separate switch 105 is provided for interrupting the circuit to the electric heater in the event it is desired to render the heating element ineffective. Thus it will be noted that all that is necessary in order to defrost the cooling element 26 is to move the doors 60 and 61 inwardly and that when the cooling ele-

ment 26 has been defrosted, the doors 60 and 61 may be returned to their normal position.

In Fig. 3 I have shown a modified form of control mechanism and cooling element. In this embodiment a cabinet 120 which corresponds to cabinet 20 is employed for the storage and display of food articles which are adapted to be cooled by a cooling element generally represented by the reference character 125. The cooling element 125 is of the flooded float controlled type and includes headers 127 and 128 forming reservoirs for liquid refrigerant the level of which I have indicated at 129 in Fig. 5. The headers 127 and 128 of cooling element 125 are interconnected by a plurality of conduits 130. The liquid level is maintained substantially constant by a float valve not shown herein but fully disclosed in the patent to Osborne 1,556,708, issued October 13, 1925.

20 Liquid refrigerant is supplied to the cooling element through a liquid conduit 135 and evaporated refrigerant is withdrawn from the cooling element through a vapor conduit 137, both conduits being suitably connected to a refrigerant circulating element 140. The element 140 includes a condenser 142, receiver 143, to which the conduit 135 is connected, a compressor 145 and a motor 147 for driving the compressor. The motor is supplied with current from the power mains 148 under the control of an automatic switch 150. The switch 150 is actuated in response to normal conditions within the system for starting and stopping the motor, and for instance, in response to change in pressure in the vapor conduit 137. The switch includes an expansible bellows 152 and suitable leverage mechanism 153 pivoted at 154.

In this embodiment I have prevented the operation of the refrigerant circulating element in response to normal conditions within the system and have arranged for simultaneously rendering a heating element 160a effective when it is desired to defrost the cooling element. I have also arranged for the automatic restoration of said means to its normal position in the event that certain abnormal conditions occur within the system to thus render the heating means ineffective to produce its function and to place the refrigerating element in readiness for operation. In this embodiment I have provided doors 160 and 161 which correspond to doors 60 and 61 for exposing the cooling element 125 to the outside air and for shutting off the food storage compartment from said outside air. I have also provided an electric fan 170 which is driven by electric motor 172 for circulating the warm outside air over the cooling element 130 during the defrosting periods and for circulating the cool air throughout the cabinet when the food storage compartment is being refrigerated. Preferably the motor 172 operates continuously.

As shown in Fig. 5 the heating element 160a has a portion thereof secured to and extending through the end wall of header 128 and has another portion thereof extending into the lowermost conduit 130 of cooling element 125 and said heating element is thereby immersed in the liquid refrigerant in the cooling element 125. Thus, it will be apparent that the heating element gives up its heat to the refrigerant which causes it to boil and circulate refrigerant throughout the entire cooling element. This causes the temperature of the walls of the cooling element to be increased, causing the ice and frost to melt and drop loose from the cooling element in large

chunks. It will also be apparent that the fan 170 (see Fig. 3) circulates warm air from the outside of the cabinet over the cooling element 125 for rapidly defrosting the cooling element.

The circuit through the heating element is 5 completed upon closure of a set of contacts 175 which takes place in a manner about to be described.

During defrosting periods of the cooling element, it is desired to render the refrigerant circulating element inoperative and in order to accomplish this, I have provided a suitable arrangement which renders the switch 150 ineffective to normal conditions within the system for causing operation of the circulating element, while 15 at the same time the circuit through the electric heating element is completed. I have provided a pivoted lever 178 which moves the leverage mechanism 153 upwardly to engage the movable member of contacts 175 to close the electric heat- 20 ing circuit and by this upward movement of the leverage mechanism the switch is moved out of its normal operating position and is ineffective to normal pressures within the bellows 152. In order to maintain the heating circuit closed and 25 to maintain the leverage mechanism 153 out of its operating position, I have provided a resilient locking device 180 which receives the handle end 181 of lever 178. This locking device keeps the lever 178 locked in position during defrosting 30 period and prevents the movement of the lever during defrosting operation. However, the lever 178 may be so arranged that when the defrosting period has been completed the pressure in the bellows will be sufficient, due to the increased 35 temperature of the cooling element 125, so that it will exert sufficient pressure on the lever 153 to move the lever 178 downwardly by means of pin 190 to thus restore the leverage mechanism and switch 150 to its normal operating position. 40 The pressure at which the bellows 152 renders the heating device ineffective and restores the switch 150 to normal operating position occurs after the cooling element has been entirely defrosted. 45

While the form of embodiment of the invention as herein disclosed, constitutes a preferred form, it is to be understood that other forms might be adopted, all coming within the scope of the claims which follow.

What is claimed is as follows:

1. Refrigerating apparatus comprising in combination, a cabinet having a food storage compartment therein, a cooling element for cooling the food compartment, a door for said cabinet, and electrical means controlled by said door for increasing the temperature of the cooling element to cause defrosting thereof. 50

2. A refrigerating apparatus comprising in combination, a cabinet having a chamber therein, means dividing said chamber into an upper cold storage compartment and a cooling element compartment disposed below said cold storage compartment, a cooling element disposed within said cooling element compartment, said means having a normally open passage therein for the circulation of air cooled by said cooling element from said cooling element compartment to said cold storage compartment, means for closing said normally open passage in said first named 60 means to isolate said compartments from air circulation therebetween, and means for exposing said cooling element compartment to atmosphere exteriorly of said cabinet while said passage is closed to defrost said cooling element. 65

70

75

3. A refrigerating apparatus comprising in combination, a cabinet having a chamber therein, means dividing said chamber into a cold storage compartment and a cooling element compartment, a cooling element disposed within said cooling element compartment, said means having a plurality of normally open passages therein for the circulation of air cooled by said cooling element from said cooling element compartment to said cold storage compartment, means for closing said normally open passages in said first named means to isolate said compartments from air circulation therebetween, means for opening a plurality of sides of said cooling element compartment to atmosphere exteriorly of said cabinet while said passages are closed, and means for creating a flow of air entirely through said cooling element compartment to defrost said cooling element.
4. A refrigerating apparatus comprising in combination, a cabinet having a chamber therein, means dividing said chamber into a cold storage compartment and a cooling element compartment, a cooling element disposed within said cooling element compartment, said means having a normally open passage therein for the circulation of air cooled by the cooling effect produced by said cooling element from said cooling element compartment to said cold storage compartment, a door for closing said normally open passage in said means for isolating said compartments from air circulation therebetween, and means controlled by said door for stopping the cooling effect produced by said cooling element to cause defrosting of same.
5. A refrigerating apparatus comprising in combination, a cabinet having a chamber therein, means dividing said chamber into a cold storage compartment and a cooling element compartment, a cooling element disposed within said cooling element compartment, said means having a normally open passage therein for the circulation of air cooled by the cooling effect produced by said cooling element from said cooling element
- compartment to said cold storage compartment, a door for closing said normally open passage in said means for isolating said compartments from air circulation therebetween, and electrical means controlled by said door for increasing the temperature within said cooling element compartment to defrost said cooling element.
6. A refrigerating apparatus comprising in combination, a cabinet having a chamber therein, means dividing said chamber into a cold storage compartment and a cooling element compartment, a cooling element disposed within said cooling element compartment, said means having a normally open passage therein for the circulation of air cooled by said element from said cooling element compartment to said cold storage compartment, and a single means for closing said normally open passage in said first named means to isolate said compartments from air circulation therebetween and for exposing said cooling element compartment to atmosphere exteriorly of said cabinet to cause defrosting of said cooling element.
7. A refrigerating apparatus comprising in combination, a cabinet having a chamber therein, means dividing said chamber into a cold storage compartment and a cooling element compartment, a cooling element disposed within said cooling element compartment, said means having a normally open passage therein for the circulation of air cooled by said element from said cooling element compartment to said cold storage compartment, a single means for closing said normally open passage in said first named means to isolate said compartments from air circulation therebetween and for exposing said cooling element to atmosphere exteriorly of said cabinet to cause defrosting of said cooling element, and means rendered effective by movement of said single means for increasing the temperature within said cooling element compartment to augment the defrosting of said cooling element.

HARRY M. WILLIAMS.
